UNITED STATES PATENT OFFICE.

GEORGE M. HENRY, OF PULLMAN, WASHINGTON.

PHONOGRAPH-RECORD-CABINET ATTACHMENT.

1,393,284.

Specification of Letters Patent. Patented Oct. 11, 1921.

Application filed November 9, 1920. Serial No. 422,788.

To all whom it may concern:

Be it known that I, GEORGE M. HENRY, a citizen of the United States, residing at Pullman, in the county of Whitman and State of Washington, have invented a new and useful Phonograph-Record-Cabinet Attachment, of which the following is a specification.

The object of my invention is to provide a cabinet having means for removing any desired record by one push button, instead of many, as in cabinets heretofore devised. It is also an object of my invention to provide a novel combination and arrangement of parts disclosed; and to provide a practical, simple, and effective apparatus for accomplishing the desired results without injury to the records. I attain these and other objects of my invention by the mechanism illustrated in the accompanying drawings, in which—

Figure 1 is a front elevation of the invention applied to a phonograph cabinet;

Fig. 2 is a vertical section through the cabinet;

Fig. 3 is a top plan of a portion of the cabinet;

Fig. 4 is a transverse vertical section on line 4—4 of Fig. 2;

Fig. 5 is a detail sectional view, partly in elevation, on line 5—5 of Fig. 2; and

Fig. 6 is a detail sectional view on line 6—6 of Fig. 2.

Like numerals designate like parts in each of the several views.

Referring to the accompanying drawings illustrating my invention, I provide a record-holding cabinet 21 which is insertable into the bottom compartment or cabinet of a disk phonograph cabinet 23. The record-holding cabinet 21 is provided with vertical partitions 22 suitably spaced to accommodate one record in each of the chambers formed by the partitions 22, and having a suitable index, such as the numeral index 24 illustrated in Fig. 1, for the several individual record compartments.

Referring to Fig. 2, I provide at the rear of the cabinet a series of record-ejecting levers 17 pivotally supported on a rod 18 which extends across the back of the cabinet in the recesses 19. Levers 17 each have a suitable projecting end 20 adapted to engage the edge of the record to be ejected.

For the purpose of operating any desired one of the series of levers 17, I provide a

push rod 2 having a rear forked end 25 adapted to releasably engage the upper end of any of the record-ejecting levers 17. Push rod 2 is provided with a push button 1 at its front end. Push rod 2 is mounted on brackets 3 and 7, which in turn are mounted on supporting arm 11. Member 11 terminates in an indicator 11', as shown in Figs. 1 and 2. I provide a spring 5 attached at one end to a fastener 6 which is secured to push rod 2 while the other end of the spring is attached to a bracket 4 which is mounted on the supporting arm 11, as shown in Fig. 3. Supporting arm 11 is slidably affixed to a shoe and arm track 13 and wood track support 14, as shown in Fig. 2. Track support 14 is mounted on the top member 16 of the record cabinet 21. The shoe 12 to which member 11 is secured is slidable in the track 13.

Extending along the top of the cabinet, I provide a suitable ratchet track 15 having its notches suitably spaced to correspond with the compartments beneath, one notch for each compartment. As shown in Fig. 6, I provide a ratchet dog 10 pressed downwardly by spring 8, the dog 10 and spring 8 being mounted in the tube 9, which is positioned on the front end of the supporting arm 11 in position for the dog to engage the ratchet track 15.

In operating the device the indicator (and with it the supporting arm 11 and push rod 2) are moved transversely on the record cabinet until the device is brought to a standstill over the compartment containing the desired record. In this position the dog 10 engages the ratchet bar 15, under the pressure exerted by spring 8, as shown in Fig. 6. Spring 15 exerts tension on push rod 2 to normally rest in its outermost position, as shown in full lines in Fig. 2. The forked end 25 of push rod 2 is adapted to engage the upper end of the desired ejecting lever 17, as shown in Fig. 3. Sliding shoe 12 is slidably mounted in the metal shoe and arm track 13, the latter being rigidly attached to track support 14. Dog 10 functions to hold the supporting arm 11 firm while the record is being ejected by push rod 2 and ejecting lever 17. The track 13 is attached to track 14 by screws, the heads of which are countersunk, leaving a smooth surface for arm 11 to slide on, as shown in Fig. 2.

The attachment cabinet 21 can be housed

in any standard make of phonograph cabinet; and it is also adapted for use as an individual sales or home cabinet.

What I claim is—

- 5 In a phonograph record attachment, the combination of a cabinet adapted to be inserted in the record compartment of a phonograph, said cabinet having a series of closely spaced vertical partitions, forming
- 10 compartments each of which is of suitable

size for one disk record, a series of ejecting levers, pivotally mounted at the rear of the cabinet one for each compartment, and a spring-controlled and forwardly pressed forked rod slidably mounted on the top of the cabinet adapted to releasably engage any one of the ejecting levers and operate same. 15

GEORGE M. HENRY.
